UNITED STATES PATENT OFFICE

2,537,447

APPARATUS AND METHOD FOR MOLDING
CONCRETE VAULTS AND THE LIKE

Peter Di Stefano, Amawalk, N. Y.

Application September 29, 1948, Serial No. 51,726

11 Claims. (Cl. 25—41)

1

This invention relates to new and useful improvements in machines for casting massive structures and the primary object of the present invention is to provide a novel and improved method and apparatus for casting burial vaults from concrete.

Another important object of the present invention is to provide an apparatus for casting massive concrete structures such as burial vaults including inner and outer mold members, and embodying novel and improved means for tamping, agitating and vibrating the concrete material poured between the inner and outer mold member to effect a setting of the concrete in a shorter period of time than was heretofore possible.

Yet another object of the present invention is to provide a machine for casting concrete vaults including a plurality of outer mold members that are fixed to a supporting frame, and means for raising a plurality of inner mold members relative to the outer mold members for casting a structure between the inner and outer mold members and for lowering the inner mold members and the cast structures.

Another object of the present invention is to provide an apparatus for casting concrete structures including inner and outer mold members, and novel and improved means for supplying a concrete mixture between the inner and outer mold members.

Another object of the present invention is to provide a machine for casting concrete burial vaults including a group of inner and outer molds that will simultaneously form the upper and lower halves of a burial vault.

Another feature of the present invention is to provide an apparatus for casting concrete vaults wherein the parts of the concrete vaults are cast in halves thus saving time and expense since the halves will be cured in approximately between eight and fifteen hours as against the present method requiring seven days.

A further object of the present invention is to provide a method for casting concrete vaults, wherein the vault will be formed in two sections which are lighter than the present type now being produced which is much heavier and requires more help in lifting.

A still further aim of the present invention is to provide an apparatus for casting burial vaults that is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference be-

ing had to the accompanying drawings forming part hereof, wherein like numerals refer to like parts throughout, and in which:

Figure 1 is a fragmentary top plan view of the present invention;

Figure 2 is a front elevational view of the present invention and showing the trays disposed above the outer mold members;

Figure 3 is a view similar to Figure 1, and with parts removed therefrom to illustrate the closure for the mixing hopper, and showing the trays disposed over the outer mold members;

Figure 4 is a diagrammatic view showing the hydraulic system used in conjunction with the present invention;

Figure 5 is a schematic view illustrating the electrical circuit used in conjunction with the present invention;

Figure 6 is an end elevational view of Figure 2 taken substantially in the direction of arrow numbered 6 thereof;

Figure 7 is an enlarged vertical sectional view taken substantially on the plane of section line 7—7 of 6;

Figure 8 is a group perspective view showing one type of vault that is cast with the apparatus of the present invention;

Figure 9 is a transverse vertical sectional view of one type of vault constructed by the present invention;

Figure 10 is a fragmentary end view of the present invention showing the tray applied to the outer mold member for forming an upper vault half having a rounded portion; and,

Figure 11 is an end view of another type of vault that is constructed by the use of the present invention, and with parts broken away for showing the manner in which the upper and lower sections are sealed.

Referring now to the drawings in detail, wherein for the purpose of illustration, there is disclosed a preferred embodiment of the present invention, the numeral 10 represents a supporting frame including a forward pair of tubular posts 12, a rear pair of posts 14 and a pair of intermediate posts 16.

Slidably engaging the forward pair of posts 12 and the intermediate pair of posts 16 are collars or rings 18 to each of which there is fixed a supporting arm 20 having bifurcated terminals 22. The bifurcated terminals 22 of the arms 20 are fixed by welding or the like to the outside corners 24 of a pair of spaced parallel, substantially rectangular outer mold members 26 and 28 that are connected by webs or cross plates 30. The end walls and side walls of the outer mold members 26 and 28 slope inwardly and upwardly and the said outer mold members are open at their upper and lower portions.

Upper and lower holding rings or collars 32 and

34 are removably secured to the forward and intermediate posts 12 and 16 by pins 36 that extend through aligned apertures 38 provided in the posts 12 and 16 and rings 32 and 34, and resilient washers or rings 40 are disposed between the rings 18 and the collars 32 and 34.

A substantially rectangular horizontally disposed base plate 42 is fixed to the rear posts 14 and intermediate posts 16 through the medium of sleeves 44 that engage the posts 14 and arms 46 having eye portions 48 that embrace the posts 16 and are secured thereto by holding pins 50.

An upper frame including criss-crossed braces 52 is provided at its ends with sockets 54 that receive and which are removably secured to the upper ends of the forward and intermediate posts 12 and 16 by any suitable means.

A transversely disposed channel member 56 is fixed to the upper frame 52 and is secured in any suitable manner, to the forward and upper portion of a hopper or mixing vat 58 that is divided into a pair of delivery compartments 60 and 62. The rear portion of the hopper 58 is supported by a pair of uprights 64 that are fixed to the base plate 42 and the hopper is thus supported above and spaced parallel to the base plate 42.

A cylinder 66 is removably secured to the base plate 42 by U-brackets or the like 68 and includes a reduced cylindrical extension 70 that slidably supports a piston rod 72. The outer end of the piston rod 72 is removably secured to the web portion of a substantially U-shaped plate 74 the lower leg 76 of which slidably engages the upper surface of the base plate 42. The upper leg 78 of the U-shaped plate 74 is elongated and supports a substantially rectangular closure plate 80 that is fixed thereto in any suitable manner. The side edges of the plate 80 slidably engage guide brackets 82 carried by the hopper 58 and normally closes the lower open end of the hopper. The rear transverse edge 84 of the closure plate 80 being flared upwardly to limit the forward sliding movement of closure plate 80 relative to the hopper.

The forward end of the piston rod 72 is fixed by welding or the like to the rear, inside corners 86 of a pair of spaced parallel trays 88 and 90 having downwardly and inwardly sloping walls. The trays 88 and 90 are open at their tops and bottoms.

Longitudinal guide strips 92 are fixed to the outer longitudinal edges of the outer mold members 26 and 28 and guide the sliding movement of the trays 88 and 90. Further angle iron guide members 94 are fixed to the inner longitudinal edges of the outer molds 26 and 28 and also aid in guiding the sliding movement of the trays.

The trays 88 and 90 are connected and braced by a web or plate 98 so that the same will move together on the base plate 42 and over the outer molds 26 and 28. Suitable stops 100 fixed to the forward end walls of the outer molds 26 and 28 limit the forward sliding movement of the trays so that the same will be disposed over the outer mold members 26 and 28.

Slidably mounted on each of the forward posts 12 and the intermediate posts 16, is an upper sleeve 102 and a lower sleeve 104. Arms 106 are fixed to the lower sleeves 104 and support a central hub 108, and downwardly inclined braces 110 are fixed at their terminals to the upper sleeves and the hub 108 to further support the latter in a substantially vertical position.

The base portion of a cylinder 112 is fixed to the central portion of the upper frame 52 and

slidably supports a piston rod 114 that is suitably secured in the central hub 108. A pair of substantially rectangular agitating frames 116 and 118 are disposed below the arms 106 and are fixed to the arms 106 by hangers 120.

Suitably fixed to the arms 106 and depending therefrom, are the base portions of a pair of spaced parallel cylinders 122 and 124 that are disposed centrally over the outer mold members 26 and 28. Slidably carried by the cylinders 122 and 124 are piston rods 126 and 128 that support agitating and tamping plates 130 and 132 which are movable through rectangular openings in the frames 116 and 118.

15 A hydraulic press or cylinder 134 is anchored beneath the outer mold members 26 and 28, and includes a vertically movable piston rod 136 to which there is secured a vibratory mounting or support 138. A plurality of longitudinal spaced walls 140 rise from the support 138 and rotatably support two rows of spaced parallel conveyor rollers 142 and 144 that are disposed beneath the outer mold members 26 and 28 respectively.

20 Vertically adjustable stop rods 146 depend from the support 138 and limit the downward movement of the support relative to the outer mold members 26 and 28.

25 Bearings 148 depend from the support 138 and rotatably support a forward transverse shaft 150 and a rear transverse shaft 152 on which there is fixed a plurality of eccentric wheels or counterweights 154. Pulleys 156 and 158 are secured to the shaft 150 and 152 and are connected by an endless belt 160. A motor 162 supported by a mounting 164 beneath the support 138 includes a drive pulley 166 that is connected to a driven pulley 168 on the rear shaft 152 by an endless belt 170. As the shafts 150 and 152 are rotated the outer extremities of the counterweights 154 on the shaft 150 will be disposed downwardly when the counterweights 154 on the shaft 152 are disposed upwardly and vice versa to impart a rocking or vibratory movement to the support 138.

30 45 A pair of inner mold members 172 and 173 are removably supported on the respective rollers 142 and 144 and include substantially rectangular bottom walls or flanges 174 that will close the open bottoms of the outer mold members 26 and 28 when the inner mold members are raised to a position where they are embraced by the outer mold members.

35 Adjacent the side edges of the bottom wall 174 of the mold member 173 there are convexed ribs that will form concaved recesses 176 in the side and end walls 178 of the lower half 180 of the present vault, and adjacent the edge of the bottom wall 174 of the inner mold member 172 there is provided a recess that will form convexed edges 182 on the side and end walls 184 of the upper half 186 of the present vault.

40 50 Tables 188 and 190 are supported forwardly and rearwardly of the support 138 and include groups of conveyor rollers 192 that lead to and from the rollers 142 and 144 so that the inner mold members may be moved to and from the support 140 in a convenient manner and comprise a conveying system.

55 The operation of the present invention is 60 classified in steps which will be briefly noted as follows:

(A) The inner mold members 172 and 173 are first conveyed by the rollers 192 on the forward table 188 to the rollers 142 and 143;

(B) The piston 136 is raised so that the inner

mold members 172 and 173 will be embraced by the outer mold members 26 and 28 with the bottom walls 174 closing the open lower ends of the outer mold members 26 and 28;

(C) The trays 88 and 90 are moved forwardly over the outer mold members 26 and 28 to dump a concrete mixture between the inner and outer mold members and is then moved back where the same will be supported in the base plate 42;

(D) The motor 162 is then started to vibrate the support 138 and the piston rods 114, 126 and 128 are reciprocated to agitate and tamp the aggregate between the inner and outer mold members or the material on the upper walls of the inner mold members;

(E) The inner mold members 172 and 173 and the cast structures are then lowered with the piston rod 136; and,

(F) The inner mold members 172 and 173 and the cast structures are then moved on the rollers 192 to a discharge point.

In order to accomplish the above operations, there is provided a hydraulic system which will now be described and which is best illustrated in Figure 4 of the drawings.

Leading from a suitable fluid pump 193, is a first conduit 194 having a plurality of branch conduits 196, 198, 200, 202 and 204 that are connected to the rear port 206 of the cylinder 66, the port 208 of the cylinder 134, and the lower ports 210, 212 and 214 of the cylinders 122, 124 and 112 respectively. A second conduit 216 branches from the first conduit 194 and includes branch conduits 218, 220, 222, 224 and 226 that are connected to the forward port 222 of the cylinder 66, the conduit 196, and the upper ports 230, 232 and 234 of the cylinders 122, 124 and 112 respectively.

A valve housing 235 is interposed in each of the branch conduits 196 and 218, 198 and 220, 200 and 222, 202 and 224, and 204 and 226 respectively and rotatably support barrel type valves 236, 238, 240, 242 and 244 that control the cylinders 66, 122, 124 and 112 in the order named. These valves each include a pair of arcuate ports 246 and 248 that communicate with the pair of conduits connected to each of the said housings.

A further valve housing 250 is interposed in the conduit 216 and supports a spring urged valve 252 that normally closes the conduit 216. An adjustable plunger 254 is carried by the housing 250 for positioning of the valve 252 in the housing to be actuated by a predetermined pressure acting upon the same to open the conduit 216.

A reservoir 256 is connected to the pump 193 by a supply line 258 so that when the pump is in operation, a fluid will be forced into the conduits 194 and 216 and hence the branch conduits leading therefrom.

A pressure gauge 260 is applied to the conduit 194 and will indicate the pressure in the said conduit.

The numeral 262 represents a panel that is suitably secured to one side of the frame 10 and which supports operating handles or pointers 264, 266, 268, 270 and 272 for the valves 236, 238, 240, 242, and 244 respectively, when the handles are turned in one direction, as shown in Figure 2, the fluid will enter the cylinders 66, 134, 122, 124 and 112, whereas when the same are turned to the opposite direction fluid will not flow to the said cylinders.

A switch 274 is carried by the panel 262 and controls the circuit for the electric pump 193 and a further switch 276 on the panel controls the

circuit to the electric motor 162 for the shafts 152, and 154. A time clock or timing mechanism 278 is supported on the panel to indicate how long the concrete mixture has been set and will also switch off and control the switches 274 and 276 to shut off the entire apparatus at a predetermined time in case the attendant is not present.

Obviously, it is not essential that the timing mechanism 278 be employed although the use of the same will provide a safety means which would add to the efficient use of the present structure.

It should be noted, that the time required for 10 vibrating and tamping the concrete mixture depends on the types of sand and gravel employed and by varying the ratio of material the required time can be for one half or one minute.

The particular shape of the inner mold will 20 permit the concrete mixture applied about the same to be retained in its packed form without slipping thus eliminating the necessity of having to retain the outer mold about the inner mold and concrete mixture during the setting of 25 the concrete in a steam room.

The switches or operating handles 268, 270 and 272 are next turned "on" and the piston rods 126, 128 and 112 will reciprocate to tamp and agitate the concrete mixture between the side 30 walls of the inner and outer mold members and the concrete mixture on the upper walls of the inner mold members, and the switch 276 is turned "on" to vibrate the support 138.

After the casket has been formed and properly processed, which takes approximately one 35 minute, the switch 274 is turned "off" and the piston rod 136 will move downwardly under the weight of the support 138, the inner mold members and the cast structures formed on the inner mold members with the stops 146 limiting downward movement of the piston 136 and support 138.

The inner mold members and the cast structures are then placed in a steam room for approximately 8-15 hours and then the inner mold members are removed to produce the desired casket, ready for use.

New inner molds are then moved into position on the rollers 142 and 144 and the process repeated.

Figure 11 illustrates the vault formed by the above described method and the upper wall 280 of the upper half and the bottom wall 282 of the lower half are both substantially flat.

In order to construct a vault 283, as shown in 55 Figures 8 and 9 whose upper half 284 includes a dome or rounded portion 286, a frame 288 is fixed to the upper portion of one outer mold, for example mold member 26 and includes end walls having convexed edges 290. The tray 88 is provided with end walls 292 having convexed edges 294 that conform to the edges 290 and thus the upper half 284 will have a rounded portion 286 when formed.

The stop 100 is carried by the forward end wall of the frame 288 and will function as previously described for limiting forward movement of the tray 88 relative to the outer mold member 26.

Having described the invention, what is claimed as new is:

1. An apparatus for casting concrete vaults and the like comprising a frame including a pair of uprights, an outer mold supported by said frame, said outer mold being hollow and including open

upper and lower portions, a support, a lift mechanism for said support, an inner mold carried by said support and including a bottom wall for closing the lower open portion of said outer mold, a slidable tray, guide means for said tray, means for moving said tray to a position over said outer mold for depositing a concrete mixture between said inner and outer molds, and a reciprocating member slidable on said uprights for agitating the concrete mixture between said inner and outer molds.

2. An apparatus for casting concrete vaults and the like comprising a frame including a pair of uprights, a plurality of outer molds supported by said frame, said outer molds being hollow and including open upper and lower portions, a support, a lift mechanism for said support, a plurality of inner molds carried by said support and including bottom walls for closing the open lower portions of said outer molds, a plurality of slid- 20 able trays, guide means for said trays, means for moving said trays to a position over said outer molds for depositing a concrete mixture between said inner and outer molds, and a reciprocating member slidable on said uprights for agitating the concrete mixture between said inner and outer molds.

3. An apparatus for casting concrete vaults and the like comprising a frame including a pair of uprights, a plurality of outer molds supported by said frame, said outer molds being hollow and including open upper and lower portions, a support, a lift mechanism for said support, a plurality of inner molds carried by said support and including bottom walls for closing the open lower portions of said outer molds, a base plate supported relative to said frame and substantially coplanar with the open upper portions of said outer molds, a plurality of slid- 35 able trays having open bottoms normally closed by said base plate, means joining said trays, guides carried by the upper portions of said outer molds slidably receiving said trays, means for moving said trays into sliding engagement with said guides, stop means carried by said outer molds for limiting sliding movement of said trays in one direction to retain the trays above the outer molds, and means for agitating a molding material between said inner and outer molds.

4. An apparatus for casting concrete vaults and the like comprising a frame including a pair of uprights, a plurality of outer molds supported by said frame, said outer molds being hollow and including open upper and lower portion, a support, a lift mechanism for said support, a plurality of inner molds carried by said support and including bottom walls for closing the open lower portions of said outer molds, a base plate supported relative to said frame and substantially coplanar with the open upper portions of said outer molds, a plurality of slid- 40 able trays having open bottoms normally closed by said base plate, means joining said trays, guides carried by the upper portions of said outer molds slidably receiving said trays, means for moving said trays into sliding engagement with said guides, stop means carried by said outer molds for limiting sliding movement of said trays in one direction to retain the trays above the outer molds, a supporting framework slidably mounted on said up- 45 rights, means for reciprocating said supporting framework, means carried by said supporting framework for agitating a molding material between said inner and outer molds, and further means carried by said supporting framework for 50

tamping the molding material between said inner and outer molds.

5. The combination of claim 4 wherein said means carried by said framework for agitating a molding material between said inner and outer molds includes a plurality of substantially rectangular plates, each of said plates having central openings for receiving said inner molds.

6. The combination of claim 4 wherein said 10 means for reciprocating said supporting framework includes a reciprocable plunger, and hydraulic pressure means for reciprocating said plunger.

7. The combination of claim 3 wherein said 15 means for moving said trays includes a cylinder mounted on said base plate, a piston rod slidably carried by said cylinder and connected to said tray joining means, and means for reciprocating said piston rod.

8. The method of casting concrete structures by the use of inner and outer mold members which includes casting the structure of concrete between the inner and outer mold members, lowering the cast structure together with the inner mold member relative to the outer mold members, then conveying the inner mold members and the cast structures to a delivery point, and finally placing the cast structure and the inner mold member in a steam room for a predetermined period of time.

9. The method of casting concrete structures by the use of inner and outer mold members, which includes the pouring of concrete between the inner and outer mold members, vibrating the inner mold members, next agitating the concrete between the inner and outer mold members, then lowering the inner mold members together with the cast structure, finally conveying the inner mold members and the cast structures to a delivery point, and thereafter placing the cast structure and the inner mold member in a steam room for a predetermined curing period.

10. The method of casting concrete structures by the use of inner and outer mold members, 45 which includes the steps of first conveying the inner mold members to a position beneath the outer mold members, raising the inner mold members, pouring concrete between the inner and outer mold members, then lowering the cast structures together with the inner mold members, finally conveying the inner mold members and the cast structure to a delivery point, and thereafter placing the cast structure and the inner mold member in a steam room for a predetermined curing period.

11. The method of claim 10 and the further step of vibrating the inner mold members during the step of agitating the concrete between the inner and outer mold members.

PETER DI STEFANO.
